Lettres. Poésie.

the Schedule, referred to in his Letter Patent and making part of the same, restraining or obstructing in the use of the said Cities, &c. Name himself, of his improvement for making patterns and Models for casting iron ware.

To all to whom these Presents shall come, I the undersigned, know that I
being the Name of Danville in the County of Columbia and State
of Pennsylvania have invented a new and useful mode and plan
in making and forming flasks & patterns and moulding iron hollow
such as hollow pipes, manifolds, cast bodies, and all other kinds of iron
hollow iron, which requires the mouth to be smaller than the body, with
a iron or flange to the mouth, and that the following is full and exact
description thereof. — Specification —

Whereas a great loss has been sustained by those engaged in the making of iron hollow bungs, arising from the manner of moulding the same with patterns cut through vertically, and the way of flasks cut in the same way with iron chucks. To obviate this difficulty and loss, I have invented the following. 1st The flask to be made of either iron or sand iron without iron chucks, cut horizontally in two places so as to make three distinct pieces with (handles in the cope and middle piece) the clay to be made with a bar across it and a hole in the middle of the bar to receive the end of the anode. The cope middle piece and clay of the flask to be joined by (Dowels and fastened with hooks & eyes) 2nd an anchor made of iron with a ring near the one end & four openings in the end ring for the purpose of pulling the sand through to form the core. this anchor to lift the core with when formed.

" But one pattern is required to form both the inside and outside of the case to facets. The pattern to be cut in two places. The widest & narrowest place so as to form three distinct pieces when held or hinged case with arms or frame are to be moulded. but if case without a

in a flange such as the kettle-gloves are to be moulded. Then the pattern is only to be cut in the middle place. Then moulding with this implement, & place the piece of the pattern for the forming the bottom of the pot or kettle on a board or iron plate outside or bottom surface and place the copper and flask over the bottom piece of the pattern. The pot for pots and the gate to form the metal. This is to be fired in the usual way. At this place come that part of the flask full of sand & thin plane board or iron plate on the flask and turn its upper side down. At this come the first board or iron plate & put on the surface of this sand & iron & some dry sand & earthy powder sand & then I put on the middle piece of the pattern and if moulding a tea kettle or pot without a rim or flange, & fill up the outside with sand after putting on the middle piece of the flask, but if moulding a pot with a rim or flange that part of the pattern which forms the rim or flange is to be, but on at the same time the second or middle piece of the pattern is put on and removed up with sand on the outside of the pattern. Then place the anchor with base of starting or last piece of the flask and put a key in the foot of the anchor and put it to its place inside of the pattern. & then run up the core with sand through the opening in the ring of the anchor until it is filled over with the upper surface of the ring then put on dry earthy sand. & then fill sand over the dry sand full of sand and take out the key which fastens the foot of the foot of the anchor in the base of the diagram. & then lay on the bottom board or iron plate and turn the flask upside down on this board or iron plate which has a vent hole in the centre. & then lift off the copper of the flask first and the bottom part or piece of the pattern and insert a iron wire into the hole in the upper end of the anchor and lift out the iron which of place for security in a stand or planks with a hole in under the lower end of the anchor. & then lift out the sand or sand & the piece of the pattern. and take off the middle piece of the flask. & then lift off the part of the pattern which forms the rim or flange of the moulding a pot. & then replace the middle piece of the flask under the iron. Then replace the copper or last piece of the flask then

near the gate so when the wheel is nearly perpendicular to the wall. By my improvement and plan it save labour and expense for purchasing patterns. one pattern being only required covering the plan, now used requires two patterns, one to form the outside and one the inside of the vessel to cast. My plan also simplifies the modelling, a boy of sixteen years of age of common capacity will learn to model in my plan in a week from his first making the attempt, whereas with the old plan it requires more experience to whom high wages are paid. My plan is more certain to cast perfect ware. There are not being liable to the surprise and as frequently happens with the present method. It also gains by making a better quality of ware of less weight out of the same kind of metal than can be made on the old plan, according to the plan now used for making the iron chocks of the flask comes in contact with the walls of the pot, is brittle and breaking the metal which requires the walls to made heavy and thick to prevent its breaking, and even with these precautions frequently breaking with the most careful handling causing great loss and disappointment. my plan having no chocks, no such effort is required every part of the ware is of the same thickness and lighter without danger of breaking by handling; ware made in the old way has a vertical ridge or lip in each side caused by the iron chocks of the flask. my plan makes the sides of the ware perfectly smooth and free from all edges.
